UNITED STATES PATENT OFFICE.

CLARENCE W. LONG AND JOSEPH W. STEPHENS, OF DALLAS, TEXAS.

WALL CONSTRUCTION.

1,232,942.

Specification of Letters Patent. Patented July 10, 1917.

Application filed April 3, 1916. Serial No. 88,708.

To all whom it may concern:

Be it known that we, CLARENCE W. LONG and JOSEPH W. STEPHENS, citizens of the United States, residing at Dallas, in the 5 county of Dallas and State of Texas, have invented certain new and useful Improvements in Wall Construction, of which the following is a specification.

This invention pertains to new and useful improvements in wall construction.

The invention contemplates the erection of a wall formed of superimposed parallel tiers or slabs spaced apart to give the wall the desired thickness; while transverse partition connect the slabs and are so arranged as to form vertical columns into which concrete is poured whereby vertical studs are produced at desired intervals as well as vertical air spaces between the studs. Such a 20 wall when completed and finished has the nature of a monolithic hollow wall.

Broadly stated walls of this character have been built and certain patents granted thereon; however in the course of evolution 25 certain improvements have been developed and our invention relates particularly to these improvements.

In carrying out the invention a slab of plastic material is provided and formed near 30 each end with a vertical groove on its inner face while its outer face has longitudinal grooves forming seats for the finishing material with which the outer side of the wall is coated. The ends of the slabs are provided with vertical grooves and the slabs 35 are made in two lengths.

In forming the wall the slabs are built up in parallel tiers spaced apart and transverse tie plates formed with vertical ribs 40 or tongues at their ends connect the tiers, the plates extending between adjacent slabs and the tongues being seated in the end grooves of the slabs. The slabs are placed in staggered relation so that the plates of 45 one course will be under the vertical grooves of the superposed course and the plates of said latter course will be over the grooves of the first course. Partition plates inserted between the slabs and engaged in the vertical grooves will coöperate with the tie 50 plate in producing vertical columns in spaced order and which may be filled with concrete whereby studs are produced.

The vertical grooves are provided near 55 each end of the slab in order to make the same interchangeable and reversible and it

is to be understood that only one groove of the slab is used. In forming a corner the slabs are permitted to project, their ends being connected by the tie plates and a suitable form is set up so that a concrete corner column or post may be formed and the slabs and plates locked into the same.

Considerable difficulty has been experienced in walls of this character in providing grounds or means for nailing or fastening base boards, frames, moldings and the like on said walls. Owing to the thinness of the slabs they cannot be plugged successfully. In overcoming this difficulty we provide wooden blocks which are used in connection with the shorter slabs and are interposed in the desired course between the ends of the slabs so as to be co-incident with the studs which provide a substantial back 75 ground for said blocks and prevent them from being displaced inwardly.

Other objects will be apparent from a perusal of the following specification and the invention will be more readily understood by reference to the accompanying drawings in which an example of the invention is shown and wherein:

Figure 1 is an isometric view of the corner of a wall constructed in accordance with the invention,

Fig. 2 is a vertical sectional view of a similar wall,

Fig. 3 is a detail of one of the slabs,

Fig. 4 is a detail of one of the shorter 90 slabs,

Fig. 5 is a detail of the tie plate,

Fig. 6 is a detail of the partition, and

Fig. 7 is a detail of the wooden block.

In the drawings the numeral 1 designates 95 a plastic slab preferably formed of a mixture of cement and sand as is common in this art. The slab is provided at each end with a vertical groove 2 while on its inner side it has a pair of vertical grooves 3, one 100 located near each end. On the outer face of the slab a pair of longitudinal grooves or seats 4 are formed and when the slabs are placed in the wall these grooves aline and form channels in which the finishing material or mortar will seat, thus obviating the use of lathing or false-work.

Tie plates 5 provided near their ends on each side with vertical ribs or tongues 6 are made in lengths which govern the thickness 110 of the wall. The plates are disposed transversely and interposed between the adjacent

ends of slabs, the tongues 6 engaging in the grooves 2, in tongue and groove relation, whereby the slabs at one end of the plate are tied to those at the other end of the plate 5 and held against lateral displacement. The slabs are laid up in two tiers or planes spaced apart and tied together by the plates.

Plastic partitions 7 have their ends 8 reduced to fit the vertical grooves 3 of the slabs. In setting up the wall the slabs are staggered or arranged in break-joint relation, so that a plate 5 will rest on a partition 7 and in the same course the adjacent partition 7 will rest on a plate 5 as indicated in 15 Fig. 2. In this way vertical columns at regular intervals will be formed and these may be filled with concrete to form studs 9. Between the studs the wall will be hollow and it will be noted that some of the grooves 20 3 remain idle.

In forming a corner the slabs are permitted to project in staggered relation but set back from the intersection of the outer vertical planes of the wall. A suitable false- 25 work or form is set up and a concrete corner post or column poured. It is obvious that certain deviations may be made to meet conditions which confront the builder.

In Fig. 4 we have shown a slab 15 which 30 in all respects is the same as the slab 1 except that it is shorter. The difference in length between the two slabs is made up by a wood block 16 having a vertical groove 17 in one edge and a vertical tongue 18 on the 35 other edge. In building a wall it is desirable in certain courses to provide means for supporting base boards, rails, moldings, frames and the like. In such courses the inner tier or plane of the wall may be 40 formed of the short slabs 15 and blocks 16, the grooves 17 receiving the tongues 6 and the tongues 18 seating in the grooves 2 of the slab. The blocks will always be disposed against the inner sides of the studs 45 which will provide a solid foundation for nailing.

By making the short slabs and blocks 50 equal in length to the long slabs a wall may be quickly and easily built with practically no mathematical problems to solve. The blocks may be formed of wood or any other material which the builder might decide to use for the purpose. These blocks may be

placed as desired and may be omitted when not necessary. The particular arrangement 55 of the partitions, tie plates and grooves 2 and 3, whereby the plates and partitions are disposed in alternate relation vertically of the wall and at the same time in staggered relation with respect to the studs, is one of 60 the very important features of the invention and gives to the wall not only a permanency but a properly bonded and substantial construction.

We claim:

1. In a wall construction the combination 65 of a plurality of slabs superimposed in spaced parallel vertical planes, tie plates interposed and engaging between the ends of the slabs and extending from a course in one vertical plane to the corresponding course in the other vertical plane, the plates and slabs being locked against lateral displacement, and partitions extending transversely 70 between parallel courses of the wall and having their ends seated in the inner sides of the slabs, said plates and partitions being disposed in alternate superimposed order and in two transverse vertical planes whereby 75 columns are formed into which concrete may 80 be poured to produce studs.

2. In a slab wall construction, a vertical side composed of superimposed vertical slabs, a second vertical side composed of superimposed vertical slabs and spaced from 85 the first side and tied thereto by plates, some of the courses of the second side having slabs arranged in spaced order, and wooden blocks filling in the spaces between the ends of said spaced slabs.

3. In a hollow slab wall construction, superimposed vertical slabs arranged in two vertical planes spaced apart, transverse plates extending from the slabs in one plane to those in the other and engaging between 95 the ends of adjacent slabs, some of the slabs being terminated short of the plates on one side, and wooden blocks inserted between the extremities of the plates and the ends of the shortened slabs, whereby said blocks and 100 plates are locked between the slabs.

In testimony whereof we affix our signatures.

CLARENCE W. LONG.
JOSEPH W. STEPHENS.
